[57] CLAIM

The ornamental design for a game controller, as shown and described.

DESCRIPTION

FIG. 1 is a perspective view of a game controller showing my new design;

FIG. 2 is a top plan view thereof;

FIG. 3 is an elevational view taken from the left side;

FIG. 4 is an elevational view taken from the right side at a slightly different angle;

FIG. 5 is an elevational view taken from the front;

FIG. 6 is an elevational view taken from the rear at a slightly different angle; and,

FIG. 7 is a bottom plan view thereof.

The broken line showing of the remainder of the game controller is for illustrative purposes only and forms no part of the claimed design.
